UNITED STATES PATENT OFFICE.

JOHN LEWIS MILTON, OF CLEVELAND, OHIO, ASSIGNOR TO THE TEAGLE COMPANY, OF CLEVELAND, OHIO, A CORPORATION OF OHIO.

DRIVING MECHANISM FOR IGNITION GENERATORS.

1,412,414.

Specification of Letters Patent. Patented Apr. 11, 1922.

Application filed February 6, 1918. Serial No. 215,720.

To all whom it may concern:

Be it known that I, JOHN L. MILTON, a citizen of the United States, residing at Cleveland, in the county of Cuyahoga and State 5 of Ohio, have invented certain new and useful Improvements in Driving Mechanism for Ignition Generators, of which the following is a specification, reference being had therein to the accompanying drawing.

10 This invention relates to mechanism for the driving of an ignition generator from the internal combustion engine with which the generator is used, the mechanism being of the type commonly known as impulse starters.

These driving mechanisms comprise a yielding connection between the driven generator shaft and a driving shaft, together with means for temporarily stopping the 20 movement of the generator shaft to permit the compression of a spring or the like, constituting a yielding connection, which is thereupon released and snaps the generator shaft forward with a quick movement so 25 that an effective spark is generated. Usually the means for temporarily stopping the movement of the generator shaft is automatically thrown out of operative position when the speed of rotation increases to a point 30 insuring generation of effective ignition currents. Then the stop device can be thrown into operation again either manually or automatically when the speed of the engine falls below a certain point.

35 One object of the invention is the provision of mechanism of this character both sensitive and positive in its operation and readily responsive to speed changes.

Another object of the invention is to produce a mechanism of this character thoroughly reliable in operation.

Another object of the invention is the provision of mechanism of the character in question having parts that are simple, substantial and capable of production at moderate cost.

50 A further object of the invention is the reduction of the number of parts of such mechanism especially by the use of means adapted both to hold the stop device in operative position, to move it into inoperative position when a certain speed of rotation is attained, and to hold it in such inoperative position.

55 Another object of the invention is the pro-

vision of improved means for throwing the stop device into operation.

Another object of the invention is the provision of a casing for enclosing the mechanism so as to render it substantially dust 60 and weather-proof and which, at the same time, is capable of being readily removed to permit free access to the parts of the mechanism.

Other objects, more or less incidental or 65 ancillary to the foregoing, will be understood from the following description in which I set forth several embodiments of my improvements by way of explanation and illustration so that the invention may be 70 clearly understood.

In the accompanying drawings,

Fig. 1 is a side elevation, partly in central vertical section, of my improved driving mechanism and the parts of the generator and engine, or engine driven parts, with which it 75 immediately co-operates.

Fig. 2 is a transverse section on the line 2—2, Fig. 1.

Fig. 3 is a transverse section on the line 80 3—3, Fig. 1.

Fig. 4 is a horizontal section on the line 4—4, Fig. 3.

Fig. 5 is a side elevation, partly in central vertical section, of a modified form of construction embodying the invention.

Fig. 6 is a transverse section on the line 6—6, Fig. 5, some of the parts being broken away to disclose certain details of the construction.

Fig. 7 is a fragmentary front elevation of a modified form of impulse starter mechanism embodying certain of my improvements.

Fig. 8 is a bottom view of certain of the parts shown in Fig. 7, to wit, the pawl, tension device and bracket upon which they are mounted.

Fig. 9 is a section on the line 9—9, Fig. 7.

Fig. 10 is a front elevation of still another 100 form of impulse starter mechanism embodying certain of my improvements.

Fig. 11 is a bottom view of certain of the parts shown in Fig. 10, to wit, the pawl, tension device and bracket upon which they 105 are mounted.

Fig. 12 is a front elevation of another form of impulse starter embodying certain of my improvements.

Fig. 13 is a bottom view of certain of the 110

parts shown in Fig. 12, to wit, the pawl, tension device and bracket upon which these parts are mounted.

Referring first to the form of construction illustrated in Figs. 1 to 4 inclusive, 1 is one of the end plates of an electric generator of the direct high tension type adapted to supply currents for ignition purposes. 2 is the rotor shaft of the generator 10 which is provided with a tapered end as shown adapted to receive suitable driving connections. On this tapered end of the shaft 2 is mounted a ratchet disk 3 which has a hub part 3^a formed to fit the tapered 15 end of the shaft 2, the shaft and hub being secured against relative rotation by a key 4, while the hub is secured against endwise movement by a nut 5. The periphery of the disk 3 is formed with two diametrically opposite ratchet teeth or shoulders 3^b, 3^c. 6 is a cam member formed with an inwardly turned hub 6^a rotatably mounted on the hub 3^a of the ratchet, and with an inwardly turned rim 6^b which carries near its inner 20 edge two diametrically opposite cam extensions 6^c, 6^d. Both the front and rear edges of these extensions are formed with cam faces 6^d. The cam extensions 6^c are relatively broad and have their inner faces 25 bearing against the outer face of the ratchet disk 3 so that the ratchet and cam parts have extensive bearing contact both at their hub and peripheral parts.

The ratchet disk 3 carries on its outer 30 face a lug or stud 7 while the cam member 6 carries a similar lug or stud 8 on its inner face. Between these studs is arranged a coiled driving spring 9 and a shorter buffer spring 10, the two springs being effectively 35 enclosed in the annular space between the ratchet and cam members.

The cam member is designed to be driven through a suitable coupling, which in the present case is in the form of an Oldham 40 coupling 11. As shown the cam member 6 is formed on its outer face with a pair of coupling lugs 11^a, 11^b which cooperate with corresponding lugs 11^c, 11^d on the driving member 11^e of the coupling. The coupling 45 member 11^e is mounted on a driving shaft 12 which projects from and may have suitable bearing support in a casing 13, which may contain any suitable form of driving mechanism such for example as gearing 50 driven from the crank shaft of an internal combustion engine in connection with which the ignition generator is used. In many instances the casing 13 may constitute an integral part of the crank case of the engine, 55 the ignition generator in such cases being commonly mounted on a platform or bracket extending from said crank case.

Directly above the ratchet and cam parts 60 is a bracket 14 which is rigidly secured by screws 15, 15 to the end plate of the gen-

erator. The bracket is formed at its outer side with a depending arm 14^a and between said arm and the base 14^b of the bracket is arranged a locking pawl 16 designed to operate with the ratchet 3 and the cam 6. 70 In the construction shown the pawl consists of a block 17 formed on its upper side with a central, longitudinally extending slot 17^a and a plate-like lever arm 18 which is rigidly secured, as by rivets 19 to the block 17. 75 The pawl thus formed is mounted on a pair of pivot screws 20, 21 as shown in Fig. 1. These pivot screws have tapered or coned ends which fit suitable apertures in the pawl and permit a nice fit of the pawl and pivot 80 parts with a minimum of friction. The pawl arm 18 has one of its ends turned at right angles to form an abutment 18^a for one end of a tension device 23 which consists of a coil spring 23^a and a link 23^b. 85 The spring and link can be formed integrally or separately, but I have here shown them formed separately and pivotably joined end to end; then the free end of the spring is attached to the abutment 18^a of 90 the pawl and the free end of the link 23^b is connected to a post 24 carried by the bracket 14.

On reference to Figs. 2 and 4 it will be observed that by reason of the bend or angle 95 in the pawl plate 18, adjacent the pivot screws 20, 21, and the relative arrangement of the post 24, the link 23^b of the tension device is disposed in the slot 17^a of the pawl; and, furthermore, the clearance between the pawl and tension device afforded by the said slot is sufficient to permit the tension device to swing across the pivot axis of the pawl when the latter is swung upward and downward. 100

The depending arm 14^a of the bracket 14 is formed with a slot 14^a to receive a plate like lever 25 which is pivotably mounted on the pivot screw 20. The lever 25 has an inturned end part 25^a which overlies and is 110 adapted to engage and press downward on the pawl 16. The opposite end of the lever 25 is normally pressed downward by a coil spring 26 mounted in a socket 14^c of the bracket 14; and the last named end of the 115 lever 25 is preferably formed with an aperture 25^b to receive a wire 27 or the like by means of which it can be turned upward against the pressure of the spring 26. 120

One objection to impulse starter mechanism as heretofore employed arises from the fact that they are exposed to dust and dirt which accumulates and interferes with the proper operation of the mechanism. To overcome this I have devised a simple but 125 highly effective method of entirely enclosing the entire mechanism. To this end I form the wall or end plate of the generator casing with an outwardly facing shoulder 1^a extending, roughly in the form of an 130

ellipse, entirely around the impulse starter mechanism. And similarly on the engine or gear casing 13 I form a corresponding outwardly facing shoulder 13^a. In the construction illustrated in Figs. 1 to 4 the said shoulders are formed by flanges integral with the generator and gear casing parts, respectively. To the shoulders 1^a and 13^a are fitted a removable case 28 which extends 10 entirely around the driving mechanism and, in connection with the walls of the generator and engine or gear casing serves to completely enclose said mechanism. The case 28 can be formed in various ways but 15 I prefer to make it of a strip 28^a of thin, flexible sheet metal which can readily be made to conform to the contour of the shoulders 1^a and 13^a. To each end of the strip 28^a are rigidly attached a pair of lugs 20 28^b which are perforated to receive screw bolts 28^c by means of which the ends of the flexible strip 28 are drawn together so that the strip is secured in place. The case 28 is formed with an aperture 28^d to permit 25 the passage of the wire 27 which can be extended by suitable connections for actuation at any desired point in relation to the engine or motor vehicle upon which the engine may be used.

30 In the operation of the above described mechanism, on starting the engine by hand crank or power starter, the motion of the driving shaft 12 is transmitted through the coupling 11 to the cam member 6 of the impulse starter mechanism proper. The motion of the cam member 6 is transmitted through stud 8, driving spring 9 and stud 7 to the ratchet 3 and generator shaft 2, the said parts moving substantially in unison 35 until the block 17 of the locking pawl, which is pressed upon the periphery of the cam 6^e by spring 23^a, engages one of the ratchet shoulders or teeth, whereby the movement of the ratchet disk 3 and of the generator shaft is stopped. Thereupon as the cam member 6 continues to rotate, the spring 9 is compressed and one of the cam faces 6^d is brought into engagement with the pawl block 17 thereby disengaging the pawl and 40 permitting the ratchet and generator shaft to snap forward under the action of the driving spring 9 in well known manner, the action of the circuit breaker and distributor of the generator being timed in relation to 45 the release of the ratchet so that the quick forward movement of the rotor is utilized for the generation of an effective ignition current. The momentum of the generator rotor at the end of its quick forward movement is absorbed by the cushion or buffer spring 10 so that the parts are not subjected to objectional shock or impact. As long as 50 the speed of the engine and the driving shaft 12 does not exceed a certain low value the 55 impulse starter mechanism continues to op-

erate in the manner described, giving two quick movements of the generator shaft during each rotation thereof. But when the speed of rotation exceeds the low value referred to the locking pawl acquires a momentum, from the action of one of the cam faces 6^d, great enough to swing the tension device 23 below the pivot axis of the pawl, whereupon the latter is thrown upward by the action of the spring against the bracket 70 75 14 and there held in inoperative position by the action of the spring 23^a. By giving the spring a suitable tension, provision can be made for throwing the starter mechanism out of operation at any desired speed, preferably at a speed lower than the engine will have in normal operation. When the engine has been stopped and it is desired to start it again the starting mechanism can readily be thrown into action by pulling on the wire 80 85 27 which swings the lever 25 and causes its inturned end 25^a to swing the locking pawl downward until the tension device swings across the pivot axis of the pawl so that the latter is pressed downward into operative engagement with the ratchet and cam. On releasing the wire 27 the lever 25 is turned by the spring 26 out of engagement with the locking pawl.

90 As will readily be understood the enclosing case 28 protects the driving mechanism from dust and dirt and also from mechanical injury. At the same time by simply removing the screw bolts 28^c the ends of the case 28 can be spread enough to permit its removal, thus giving free access to the mechanism.

95 As will be apparent to those familiar with mechanism of this character, I have produced an impulse starter mechanism having parts that are simple and rugged and adapted to operate in a uniform and reliable manner. By the use of a resilient tension device for the control of the locking pawl, the pawl mechanism is rendered sensitive in 100 operation since the number of working joints is reduced to a minimum and these joints, because they are under tension, can be made to work with less friction than would be possible with a spring under compression. Furthermore the tension device for controlling the locking pawl not only has the advantage of a small number of 105 parts and a minimum of friction but also is adapted to perform the double function of holding the locking pawl either in an operative position or in an inoperative position.

110 The advantage of my improved means for throwing the locking pawl into operation is obvious since it provides for the performance of the function in a simple and convenient manner, and, because it is unattached to the locking pawl, cannot interfere with its proper operation.

115 120 125 130 In the construction illustrated in Figs. 5

and 6 I have sought to make use in a large measure of steel stampings, that is to say to shape the parts by die press methods rather than machine cutting methods. In other respects the construction is similar to that above described and the operation of this second form of construction is entirely like that above described. A brief description will therefore suffice.

31 is the end plate of an ignition generator having a rotor shaft 32 tapered at one end to receive a ratchet hub 33 which is secured against relative rotation by a key 34 and against endwise movement by a nut 35. 36 is a ratchet disk stamped from steel and fixedly secured to the hub 33. Preferably the hub is toothed or serrated and the disk 36 formed with a similarly shaped aperture so that when the disk is pressed on the hub it is secured against rotation in relation thereto. The periphery of the disk 36 is formed with two diametrically opposite ratchet teeth or shoulders 36^a, 36^b.

A sleeve 37 is rotatably mounted on the hub 33 and on this sleeve is fixedly secured a cam disk 38. As in the case of the inner end of the hub 33, the outer end of the sleeve 37 is toothed or serrated, as indicated at 37^a, Fig. 6, and the cam disk 38 has its central aperture similarly formed so that when it is pressed on the sleeve 37 it is fixedly secured thereto. The disk 38 is cupped as indicated in Fig. 5 and has its inner surfaces near its periphery bearing against the outer surfaces of the ratchet disk 36 thus forming between said parts an annular chamber in which is mounted a driving spring 39 and a buffer spring 40; as in the case of the first described construction, the spring having engagement at their ends with lugs or studs one of which is carried by the disk 36 and the other by the disk at 38. On its outer periphery the disk 38 is formed with two diametrically opposite cam extensions 38^a, 38^b having cam faces 38^a, 38^b.

Above the ratchet and cam disks of the starting mechanism is a bracket 41 rigidly secured by screws 42 to the face of the end plate 31 of the generator. This bracket 50 carries a locking pawl 43, a pawl controlling tension device 44, and a lever 45 for throwing the pawl into operative engagement, all of these parts being similar in construction, arrangement and operation to the corresponding parts of the first described mechanism.

The cam disk 38 of the starter mechanism is driven from shaft 46, which projects from engine gear casing 47, through a coupling 48. This coupling comprises two stamped steel disks 48^a, 48^b which are formed with peripheral interlocking teeth 48^a, 48^b, respectively. The disk 48^a has a serrated central aperture and is mounted on the end 65 of the sleeve 37 with a pressed fit, while the

coupling disk 48^b is similarly or otherwise attached to a hub 48^c which is secured by pin 49 to the shaft 46.

As in the first described construction I provide a sheet metal case 50 to enclose the driving mechanism, but instead of providing supporting shoulders for the case 50 in the form of integral flanges on the generator plate 31 and the gear casing 47, I mount cup-shaped steel stampings 51 and 52 on said end plate and casing respectively. The stamping 51 is formed with an aperture to fit the boss or extension 31^a of the end plate 31, and at its outer periphery is struck up with a flange 51^a to receive the case 50. The stamping 51 is effectively secured to the end plate 31 of the generator by the screws 42, 42 which serve to secure the bracket 41 thereto. Similarly the stamping 52 is centrally apertured and is formed at its periphery with a struck up flange 52^a to receive the case 50. The stamping 52 is secured in a suitable manner, as by screws 53, to the gear casing 47. The case 50 is secured in position by screw bolts 50^a in lugs 50^b secured to the ends of the sheet metal strip forming said case.

As has been stated, the operation of this second form of construction is similar to that previously described and it will, therefore, be understood without further explanation.

In Figs. 7, 8 and 9 I show a modified form of the impulse starter mechanism. 61 represents the end plate of the ignition current generator, 62 its shaft, 63 a ratchet keyed on the end of the shaft and secured by a nut 64, 65 a cam member and 66 a driving spring. These parts are substantially the same as the corresponding parts shown in Figs. 1 to 4, inclusive, except that the cam member is formed on its outer face with a flange 65^a that entirely surrounds the nut 64, said flange being formed with notches 65^b designed to receive the co-operating lugs of a driving coupling member.

In the present case the stopping pawl mechanism is mounted below the ratchet and cam devices instead of above them. 67 is a bracket rigidly secured by screws 68 to the end plate 61 of the generator. This bracket carries a pivot stud 69 on which is mounted a stopping pawl 70 designed to engage the ratchet and be engaged by the cam. The pawl is formed by bending a strip of metal, preferably stamped from suitable sheet material, back upon itself, the middle of the strip thus forming the ratchet-engaging end 70^a of the pawl while the two ends of the pawl are rigidly connected by a pin 70^b which is secured by riveting. A nut 71 serves to retain the pawl on the stud 69.

The pawl is yieldingly held either in operative or inoperative position by a resilient tension device 72 comprising a coiled spring 130

72^a and a link 72^b. One end of the spring is joined to one end of the link and the other end of the spring is attached to the pin 70^b, while the second end of the link is pivotally connected to a stud 73 on the bracket 67. The link 72^b is offset in relation to the pivot stud 69 of the pawl as indicated in Fig. 7 so that the longitudinal axis of the tension device is permitted to swing across the pivot axis of the pawl. Thus, as in the case of the previously described constructions, the tension device serves to hold the pawl either in operative or inoperative position. 74 is a stop to limit the movement of the pawl 70 when it is moved to its inoperative position.

In the operation of this form of mechanism the locking pawl, under the control of the tension device, co-operates with the ratchet and cam mechanism in substantially the same manner as has been set forth in connection with the previously described constructions so that the operation need not be described in detail.

In Figs. 10 and 11 I show a modified form of the type of construction illustrated in Figs. 7, 8 and 9, the only differences being in the form of the locking pawl its tension device and the bracket upon which said parts are mounted. 81 designates the end plate of the generator, 82 the ratchet and 83 the cam. The yoke-shaped bracket 84 is secured to the end plate 81 and between the arms 84^a, 84^b of this bracket is arranged a locking pawl 85 which is pivotally supported on a pin 86. The locking pawl comprises side plates 85^a, a pivot block 85^b, a ratchet-engaging end block 85^c and a pin 85^d, said blocks and pin securing the side plates rigidly together in spaced relation as indicated in Fig. 11.

The locking pawl is controlled in part by a tension device 87 comprising a coiled spring 87^a and a bent link 87^b, the spring and link in the present case being formed in one part. The spring end of the tension device is pivotably connected to the pin 85^d while the link end is connected to the end of a screw 88 adjustably mounted in the bracket 84. By disengaging spring 87^a from the screw 88 the latter can be adjusted to vary the tension of the spring. As indicated in Fig. 10 the link section 87^b of the tension device is laterally offset to permit the longitudinal axis of the tension device to swing across the pivot axis of the locking pawl, thus adapting the tension device to hold the locking pawl either in operative or in inoperative position. In its inoperative position the pawl is pressed against a stop 89 by the tension device.

The operation of this last described mechanism is similar to that of the mechanism shown in Figs. 7, 8 and 9 and will be understood without further explanation.

In Figs. 12 and 13 I show still another form of construction for the locking pawl and tension devices of the type of mechanism illustrated in Figs. 7, 8 and 9. 91 is the end plate of the generator, 92 the ratchet 70 and 93 the cam. 94 is a bracket rigidly secured to the end plate 91 and provided with a pivot stud 95 on which is mounted a locking pawl 96. The locking pawl is roughly V shaped in side elevation, as appears from Fig. 12, and is preferably formed by bending a stamping of suitable sheet metal so that the middle part of the stamping forms the ratchet engaging end 96^a of the pawl while the free ends of the stamping are rigidly joined by a rivet pin 97.

Co-operating with the locking pawl is a tension device 98 comprising a coil spring 98^a and a sheet metal link 98^b pivotably connected to the spring. The free end of the spring is pivotably connected to a stud 99 on the bracket 94 while the free end of the link is similarly connected to the pin 97 of the locking pawl. The link 98^b is formed with a large aperture 98^b' permitting it to swing through a considerable range in relation to the pivot stud 95. One arm of the pawl is formed with a lug 96^b arranged to co-operate with a stop pin 100.

As will be readily understood the operation of the mechanism shown in Figs. 12 and 13 is substantially the same as that shown in Figs. 7, 8 and 9.

It will be understood that the various features of my invention can be embodied in forms of construction other than those illustrated and that the constructions illustrated are to be treated as explanatory and not as defining the scope of my invention.

What I claim is:

1. In a driving mechanism for ignition generators, the combination with the generator shaft of means for driving said shaft comprising a ratchet fast on the generator shaft, a cam mounted to turn in relation to said generator shaft, a spring interposed between the cam and ratchet to transmit power to drive the generator shaft, a pivoted locking pawl arranged to engage and stop the ratchet and be disengaged therefrom by the cam, and a resilient tension device connected at one end to a fixed abutment at one side of the pivot axis of the pawl and at its other end to the pawl at the opposite side of said axis, the pawl and tension device being constructed and arranged to permit the latter to swing across the pivot axis when the pawl is moved from its operative to its inoperative position in relation to the ratchet.

2. In a driving mechanism for ignition generators, the combination with the generator shaft of means for driving said shaft comprising a ratchet fast on the generator shaft, a cam mounted to turn in relation to said generator shaft, a spring interposed be-

tween the cam and ratchet to transmit power to drive the generator shaft, a pivoted locking pawl arranged to engage and stop the ratchet and be disengaged therefrom by the 5 cam, and a tension device having a coil spring section and a link section connected thereto, one end of the tension device being connected to a fixed abutment at one side of the pivot axis of the pawl and the other 10 end being connected to the pawl at the other side of said axis and one of the pawl and tension device parts being laterally offset relatively to the pivot axis to permit the tension device to swing across the said axis 15 when the pawl is moved from its operative to its inoperative position in relation to the ratchet.

3. In a driving mechanism for ignition generators, the combination with the generator shaft of means for driving said shaft comprising a ratchet fast on the generator shaft, a cam mounted to turn in relation to said generator shaft, a spring interposed 20 between the cam and ratchet to transmit power to drive the generator shaft, a pivoted locking pawl arranged to engage and stop the ratchet and be disengaged therefrom by the cam, and a resilient tension device connected at one end to a fixed abutment at 25 one side of the pivot axis of the pawl and at its other end to the pawl at the opposite side of said axis, and said pawl being formed with an open space extending longitudinally of the pawl across its said pivot axis, whereby the tension device is permitted 30 to swing across the said axis when the pawl is moved from its operative to its inoperative position in relation to the ratchet.

4. In a driving mechanism for ignition generators, the combination with the generator shaft of means for driving said shaft comprising a ratchet fast on the generator shaft, a cam mounted to turn in relation to said generator shaft, a spring interposed 40 between the cam and ratchet to transmit power to drive the generator shaft, a pivoted locking pawl arranged to engage and stop the ratchet and be disengaged therefrom by the cam, and a tension device comprising a 45 coil spring section and a link section connected thereto, one end of the tension device being connected to a fixed abutment at one side of the pivot axis of the pawl and the other end being connected to the pawl at the 50 other side of said axis and one of the pawl and tension device parts being laterally offset relatively to the said axis to permit the tension device to swing across the axis when the pawl is moved from its operative to its 55 inoperative position in relation to the ratchet.

5. In a driving mechanism for ignition generators, the combination with the generator shaft of means for driving said shaft comprising a ratchet fast on the generator 60

shaft, a cam mounted to turn in relation to said generator shaft, a spring interposed between the cam and ratchet to transmit power to drive the generator shaft, a locking pawl to engage and stop the ratchet and be disengaged therefrom by the cam, means adapted to hold the pawl in inoperative position, and manual movably mounted means adapted when manually actuated to engage the pawl in its inoperative position 70 and move it to an operative position, the pawl being movable in operation from one operative position to another independently of the said manual means.

6. In a driving mechanism for ignition generators, the combination with the generator shaft of means for driving said shaft comprising a ratchet fast on the generator shaft, a cam mounted to turn in relation to said generator shaft, a spring interposed 75 between the cam and ratchet to transmit power to drive the generator shaft, a locking pawl to engage and stop the ratchet and be disengaged therefrom by the cam, means adapted to hold the pawl in inoperative position, and a manual lever adapted when manually actuated to engage the pawl in its inoperative position and move it to an operative position, the pawl being movable in operation from one operative position to 80 another independently of the said manual lever.

7. In a driving mechanism for ignition generators, the combination with the generator shaft of means for driving said shaft comprising a ratchet fast on the generator shaft, a cam mounted to turn in relation to said generator shaft, a spring interposed 85 between the cam and ratchet to transmit power to drive the generator shaft, a pivoted locking pawl arranged to engage and stop the ratchet and be disengaged therefrom by the cam, means adapted to hold the pawl in inoperative position, and a manual lever mounted to turn about the axis of the 90 pawl pivot and adapted when manually actuated to engage the pawl in its inoperative position and move it to an operative position, the pawl being movable in operation from one operative position to another independently of the said manual lever.

8. In a driving mechanism for ignition generators, the combination with the generator shaft of means for driving said shaft comprising a ratchet fast on the generator shaft, a cam mounted to turn in relation to said generator shaft, a spring interposed 100 between the cam and ratchet to transmit power to drive the generator shaft, a locking pawl to engage and stop the ratchet and be disengaged therefrom by the cam, means adapted to yieldingly hold the pawl in inoperative position, and manual movably mounted means adapted when manually actuated to engage the pawl in its inoperative 105 position.

position and move it to an operative position, the pawl being movable in operation from one operative position to another independently of the said manual means.

5 9. In a driving mechanism for ignition generators, the combination of a generator having a casing and a rotor shaft projecting through a wall of said casing, a gear casing adjacent to which the generator is mounted, 10 a driving shaft projecting from said gear casing, an impulse starter mechanism forming a driving connection between the generator shaft and said driving shaft, and a removable case extending between the adjacent walls of the generator and gear casings to completely enclose the starter mechanism.

10 10. In a driving mechanism for ignition generators, the combination of a generator 20 having a casing and a rotor shaft projecting

through a wall of said casing, a gear casing adjacent to which the generator is mounted, a driving shaft projecting from said gear casing, an impulse starter mechanism forming a driving connection between the generator shaft and said driving shaft, the opposite walls of the generator and gear casings having outwardly facing shoulders surrounding the generator and driving shafts respectively, and an enclosing case 25 for the starter mechanism comprising a flexible metal band extending around said mechanism with its edge parts engaging said shoulders and means on the two ends of said band to detachably secure them together. 30 35

In testimony whereof, I hereunto affix my signature.

JOHN LEWIS MILTON.
